MULTIPLE VALVE FOR CONDENSER TUBE BLOWERS

Filed Jan. 17, 1946

UNITED STATES PATENT OFFICE

2,593,101

MULTIPLE VALVE FOR CONDENSER TUBE BLOWERS

William S. Campbell, Astoria, N. Y.

Application January 17, 1946, Serial No. 641,776

5 Claims. (Cl. 277—43)

1

My invention relates to tube cleaners and in particular to devices for applying high-pressure fluids such as steam directly to flue or condenser tubes for flushing the same.

A number of devices have been proposed and are in use for supplying pressurized fluids to condenser tubes for cleaning purposes. Most of these devices require manual actuation of a valve in order to admit the cleaning fluid. Frequently, the tubes to be cleaned are constricted by excessive deposits, so that application of pressurized fluid may result in the backward ejection of cleaning fluid. When steam is employed, this difficulty can result in serious injury to the user of the device.

It is, accordingly, an object of my invention to provide an improved tube cleaner of the character indicated.

It is another object to provide a tube-cleaning device offering improved features of safety and of operating ease.

It is also an object to provide a tube-cleaning device having an improved automatic valving mechanism for readily admitting pressurized cleansing fluid only when the device is properly fitted to the tube to be cleaned.

It is a further object to provide an improved tube-cleaning device in which valving means automatically admits pressurized fluid to a pipe to be cleaned only when the device is urged against the pipe.

Other objects and various features of novelty and invention will be hereinafter pointed out or will become apparent to those skilled in the art.

In the drawings which show, for illustrative purposes only, a preferred form of the invention:

Fig. 1 is a cross-sectional elevation of my improved tube-cleaning device, shown with the valving mechanism in its normally closed position;

Fig. 2 is a sectional view of a portion of the device shown in Fig. 1, illustrating the valving mechanism in its open position; and

Fig. 3 is a section taken in the plane 3—3 of Fig. 1.

Broadly, my invention resides in the provision of an improved automatic valving mechanism for a tube cleaner having an input chamber 5 and a discharge-orifice member or nozzle 6. The valving mechanism is normally seated to seal off chamber 5 from orifice member 6. Member 6 is adapted for displacement with respect to chamber 5, and means are provided for opening the valve mechanism upon displacement of nozzle 6. In operation, nozzle 6 is displaced only

2

when the device is urged against the open end of a tube to be cleaned. This action results in opening the valve—thus admitting pressurized cleaning fluid to the tube to be cleaned. If the device is insufficiently urged against the tube, or if the tube has been flushed and the device is being removed, the pressure of the fluid in chamber 5 over the upstream area of the valve is sufficiently great to force an immediate closure of the valve. Thus, before the valve is actually removed from the tube, complete closure has been effected and the danger of fluids escaping from the interfit of discharge member 6 with the tube is very substantially reduced.

15 In complete form, the valve means of my invention includes a first member which is normally seated to cut off the major part of the possible flow between chamber 5 and nozzle 6. A second or pilot-valve member is normally seated to cut off the remainder of this possible flow, and this second valve is positioned to coat with displacement of member 6. In operation, since the second valve presents a comparatively small upstream area, the device may be urged with relative ease into operating relation with the tube to be cleaned. Opening of the second valve member admits fluid at high-pressure to the downstream side of the first valve member, thus partially balancing the pressures on the main valve and making possible easy complete opening of the valve.

30 Referring to the form shown in the drawings, the device is built around a main body or housing 7 having a handle 8 for portability and to facilitate urging the device against a tube to be cleaned. Main body 7 includes chamber 5 at its upstream end and an inlet pipe 9 for connection to a source of supply of cleaning fluid. Orifice member 6 is in sliding engagement with the housing 7, and in the form shown this fit is concentric—that is, an outer cylindrical portion 10 is displaceable longitudinally in a sleeve 11 forming a part of housing 7. If desired, and particularly when high-pressure fluids are employed, sealing means may be provided to prevent leakage between the sliding surfaces 10 and 11; in the form shown, a cup 12 threadededly engages housing 7 to urge packing 13 into relatively tight engagement with surface 10.

40 As indicated above, my improved valving mechanism comprises essentially two parts. A first or main valve member 14 is normally seated at the downstream end of the chamber 5. In the form shown, valve member 14 includes passages 15 permitting fluid communication between chamber 5

and discharge member 6. Normally, however, this communication is prevented by the seated relation of a second or pilot-valve member 16 over openings 15. In the form shown, valve member 14 is provided with an inner sleeve 17 slidably accommodating both the stem 18 of pilot valve 16 and a rod 19 for a purpose which will later be clear. Valve member 14 also includes a cylindrical guide section 20 to promote axial alignment of the entire valve mechanism with housing 7 and a free sliding relation between these elements. Once pilot valve 16 has been displaced to an open position, a number of openings 21 between an inner annular space 22 (at the downstream end of orifices 15) and an outer annular space 23 permit communication of pressurized fluid to substantially the entire downstream cross-sectional area of valve member 14, thus partially balancing the forces acting on main valve 14.

To improve alignment of parts and to retain orifice member 6 in unit-handling relationship with the tube-cleaning device as a whole, valve member 14 is provided with a further cylindrical portion or sleeve 24 extending in sliding engagement substantially down a sleeve 25 machined in orifice member 6. Sleeve 24 is formed at its downstream end with a pair of diametrically opposed slots 26 accommodating an anchoring pin 27 held in member 6. Pin 27 may be secured in member 26 by conventional methods, and in the form shown, a spring wire or snap ring 28 extends circumferentially about member 6 in a groove 29 machined in a plane containing pin 27.

Pin 27 also carries rod 19, and the location of slots 26 is such that, in the normal extended position of member 6, rod 19 will be spaced from stem 18 to permit the concurrent seating of pilot valve 16 and of valve member 14. It will be noted that discharge-orifice member or nozzle 6 is provided with a shoulder 30 and that this shoulder may abut the lower end of cup 12, thus limiting the upstream displacement of member 6. The extent of slots 26 should be such that pin 27 will engage cylindrical portion 24 to unseat valve member 14 prior to abutment of shoulder 30 with cup 12. The length of rod 19 should be such with respect to the length of slots 26 that valve 16 is unseated before the above-mentioned operation of valve 14.

As explained, the parts of my tube-cleaning device are normally arranged as shown in Fig. 1, the high-pressure cleaning fluid serving to keep both valves 14 and 16 seated automatically. The device is adapted for use by insertion of nozzle member 6 into the tube to be cleaned (see the dot-dashed element in Fig. 2). Depending upon its size, the end of the tube will abut one of shoulders 31-32 on member 6. By thrusting against handle 8, the user can readily force an opening of pilot valve 16—thus admitting a restricted flow of cleaning fluid to the tube and, more particularly, to the downstream effective area of valve 14. This condition necessarily means a relatively small force differential tending to keep valve 14 seated; this differential may be readily overcome by an additional thrust on handle 8, whereby pin 27 engages the cylindrical portion 24 of valve 14 to unseat the same. Both valves 14 and 16 are then unseated and admit through orifices 21 and 15, respectively, full flow of cleaning fluid at high pressure.

In removing the device, when it is considered that a cleaning operation has been completed, a first decrease in thrust will disengage pin 27 from

sleeve portion 24 and permit the above-mentioned pressure differential to seat main valve 14—thus substantially cutting off the flow of cleaning fluid. With subsequent decreases in thrust, and since pilot valve 16 presents a larger effective area upstream than downstream, the fluid-supply pressure in chamber 5 immediately forces a closure of valve 16. Thus, just before the thrust is removed from handle 8, the entire valving mechanism has been automatically closed and a harmful escape of cleaning fluid is not possible from the interfit of member 6 (at shoulder 31 or 32) with the pipe that has just been cleaned or that it was not possible to open by this method.

For improved performance of my valving mechanism, I prefer to employ a material such as brass for the members 14 and 16 and steel or other hard material for rod 19. Under these circumstances, repeated abutment of rod 19 with the stem 18 of the pilot valve would cause excessive wear of the brass member. To reduce this wear I have, in the form shown, embedded a steel ball 34 in valve stem 18.

When the described tube-cleaning device is not in operation and is to be stored, the absence of a pressure-differential across pilot valve 16 means that this element will freely "float" in valve 14. To prevent permanent dislocation of these valve parts, there is provided in chamber 5 a ledge 35 against which pilot valve 16 may abut, if necessary. It will be clear that even if both valves have become unseated while not in use, reapplication of high pressures to the inlet chamber 5 will effect immediate valve closure—thus readying the device for use.

While the invention has been described in considerable detail and a preferred form illustrated, it is to be understood that various changes and modifications may be made within the scope of the invention as defined in the appended claims.

I claim:

1. In a tube-cleaning device, a housing including a sleeve, a discharge member slidable in said sleeve, a main valve, a pilot valve, lost-motion means connecting said discharge member to said pilot valve, said lost-motion means being operative to open said respective valves in response to displacement of said discharge member in one direction, and lost-motion means connecting said discharge member to said main valve, the motion lost by said second-mentioned lost-motion means being greater than the motion lost by said first-mentioned lost-motion means, whereby first incremental displacement of said discharge member with respect to said sleeve in said one direction is effective to take up lost motion only, further incremental displacement in said one direction is effective to open said pilot valve and still further incremental displacement is effective to open said main valve.

2. In a tube-cleaning device, a housing including a sleeve and an inlet for pressurized fluid, a discharge member slidable in said sleeve, a generally annular main valve having portions slidable in said sleeve and in said discharge member, a pilot valve seatable on said main valve, said main valve and said pilot valve being between said inlet and said discharge member, first lost-motion means between said discharge member and said pilot valve, and second lost-motion means between said discharge member and said main valve.

3. In a tube-cleaning device, a housing having a longitudinal bore, a discharge member and a main valve slidable in said bore, a pilot-valve

member positioned on said main valve to be unseated by a displacement of said discharge member relatively to said housing when the discharge member is inserted into a tube to be cleaned, said main valve and said pilot-valve member being disposed so as to be urged into closed position by pressure in said housing, and a lost-motion connection between one of said members and said main valve, whereby after said pilot-valve member has been opened by a first displacement of said discharge member in one direction, said main valve may be opened upon a further displacement of said discharge member in said one direction, said housing sealingly encasing said main valve and one end of said discharge member, whereby said main valve and said pilot-valve member may be self-closing upon removal of said discharge member from a tube, and further whereby in the case of a constricted tube to be cleaned there may at all times be a safe containment of pressures within said housing.

4. A device according to claim 3, in which abutment means on said discharge member serves to limit outward longitudinal displacement of said discharge member relatively to said housing.

5. A device according to claim 3, in which there is a further lost-motion relation between said discharge member and said pilot-valve member, and in which there is a substantial effective

5 cross-sectional area of said discharge member facing generally upstream within said device, said substantial area exceeding the effective downstream-facing cross-sectional area of said discharge member that is to be inserted in a tube to be cleaned, whereby the pressure within said device may exert a resultant force tending to displace said discharge member in the opposite direction to the extent of said further lost-motion upon withdrawing said device from a tube and after said pilot-valve member has closed itself.
